CONTROL SYSTEM FOR ELECTRIC CURRENT RECTIFIERS

Application filed August 19, 1930, Serial No. 476,338, and in Germany August 28, 1929.

The invention relates to improvements in control systems for electric current rectifiers of the type employing an electric arc flowing through a vapor having a valve action thereon and, particularly, to a control system in which the flow of the arc is controlled by grids which may be either positively or negatively charged.

Electric current rectifying structures and systems employing controllable grids are known but such systems generally require an auxiliary direct current source to charge the grids at the potential desired. Such auxiliary direct current sources undesirably complicate the system and furnish an additional point at which failure of the system may occur. It has been found however that various metallic portions arranged in insulated relation in the arc path within the rectifier, during the passage of the arc therethrough, take on a potential intermediate that of the anodes and that of the cathode. Such metallic portions may, therefore, be used as sources of direct current to charge the control grids with a positive potential thereby avoiding the use of an auxiliary direct current source for that purpose.

It is, therefore, among the objects of the present invention to provide an electric current rectifier control system in which the potential impressed on the control grids is taken from a metallic portion arranged within the rectifier.

Another object of the invention is to provide an electric current rectifying control system in which the potential impressed on the control grids is taken from a metallic structural portion of the rectifier in contact with an arc other than the actual rectifying arc.

Objects and advantages, other than those above set forth, will be apparent from the following drawing when read in connection with the accompanying description in which

Figure 1 diagrammatically illustrates one embodiment of the present invention in which auxiliary anodes and grids form the source of supply of the potential required for controlling the main rectifying arc,

Figure 2 diagrammatically illustrates one

modification of the structure shown in Fig. 1, in which modification the control potential is produced in a device separate from the main rectifier, and

Figure 3 diagrammatically illustrates a further modification of the system in which the supply grids shown in Figs. 1 and 2 are eliminated and the metallic tank of the auxiliary rectifier itself is used as the control potential source.

Referring more particularly to the drawing by characters of reference, the reference numeral 4 designates an electric current rectifier which, as diagrammatically indicated in the drawing, may be of the metallic casting type, having a plurality of main anodes 6 and a cathode 7 of suitable vaporizable material, such as mercury, having a valve action on an electric arc flowing between the anodes and the cathode. The anodes each have a control grid 8 arranged between the anode and the cathode, on which grids the potential required for controlling the action of the main arc is impressed.

The potential supplied to the control grids 8 is supplied from grids 9 arranged adjacent the auxiliary or excitation anodes 11 to which current is supplied from a transformer 12. The supply grids 9 are in the path of the arc flowing from the excitation anodes 11 to the cathode and out of the path of the arc flowing from the main anodes 6 to the cathode. The supply grids 9 are connected with the control grids 8 by means of a resistance and a reversing switch. As shown in Fig. 1 of the drawing the potential supplied to the control grids 8 from supply grids 9 is positive and is limited by the resistance 13. The switch 14 may however be reversed to connect the control

grids 8 through an ohmic resistance 16 and an excitation current limiting resistance 17, with the cathode 7 and the neutral point of the transformer 12 to obtain a negative potential with respect to the anodes whenever such becomes necessary for proper control of the rectifying action. The arc flowing between the excitation anodes 11 and the cathode 7 impresses a positive potential on the supply grids 9. The value of such posi-

tive control potential may be adjusted by enclosing or shielding the auxiliary arc from the main arc. The control system is preferably formed as a multiphase system so that the supply grids 9, which are conductively connected, are at substantially a constant positive potential relative to that of the cathode.

The control potential may also be produced in a device separate from the work circuit which is supplied by the rectifier, as shown in Fig. 2, in which the transformer 12 supplies current to a plurality of anodes 21, 22 and 23 arranged in a separate rectifier 24 having a cathode 26 connected with the cathode 7 of the main rectifier 4. The arc flowing in the auxiliary rectifier 24 impresses a positive potential on the supply grids 27, 28 and 29 which may then be supplied to the control grids 8 over resistances 13 and reversing switch 14 as above described. The operation of switch 14 to its alternate position will, however, connect the control grids 8 with the cathode 7 through current limiting resistances 16, 17 and thereby impress a potential negative with respect to the anodes 6 on the control grids 8 as in the embodiment according to Figure 1 of the drawing. In this modification of the system, the control positive potential is thus produced in a device separated from the main rectifier and disturbances in one will be without effect on the other. The potential impressed on the supply grids can also be more accurately controlled than if both supply and control grids are present in the same structure.

As illustrated in Fig. 3, the metallic tank itself of the auxiliary rectifier 24 above mentioned is used as the source of control positive potential thereby avoiding all use of the supply grids. As explained with reference to Figures 1 and 2 of the drawing the movement of switch 14 to its alternate position operates to impress a potential on the control grids 8 negative with respect to the associated anodes 6. The advantages of the present construction are that the insulated grids and the insulating bushings for the conductors leading to the grids are eliminated thereby materially simplifying and cheapening the construction.

It will thus be seen that the present invention provides a control system for electric current rectifiers in which the use of an auxiliary direct current source of potential is avoided and portions of the rectifying structure itself are used to supply the control potential to the control grids thereof. Either a positive or a negative potential may be obtained as desired by a simple and inexpensive means and the value of such potential may be regulated as may appear to be necessary.

Although but a few embodiments of the

present invention have been illustrated and described, it will be apparent to those skilled in the art that various changes and modifications may be made therein without departing from the spirit of the invention or 70 from the scope of the appended claims.

The invention claimed is:

1. In an electric current rectifier control system, an electric current rectifier comprising a tank, a cathode within said tank, 75 anodes extending into said tank, control grids arranged adjacent said anodes, and means arranged in the path of an arc other than the arc flowing from said anodes to said cathode operative to supply a potential to said grids for controlling the rectifying action.

2. In an electric current rectifier control system, an electric current rectifier comprising a tank, a cathode within said tank, 85 anodes extending into said tank, control grids arranged adjacent said anodes, means for producing an electric arc auxiliary to that flowing between said anodes and said cathode, and means arranged in the path of 90 the auxiliary arc operative to supply a positive control potential to said control grids.

3. In an electric current rectifier control system, an electric current rectifier comprising a tank, a cathode within said tank, main 95 anodes extending into said tank, control grids arranged adjacent said main anodes, anodes for producing an electric arc auxiliary to that flowing between said main anodes and said cathode, grids arranged in 100 the path of the auxiliary arc to receive a positive potential, and means for connecting said supply grids and said control grids to govern the flow of current from said main anodes to said cathode.

4. In a control system for electric current rectifiers of the arc type, an electric current rectifier, means for producing an operating arc within said rectifier, means for producing an auxiliary arc within said rectifier, 110 means in the path of the operating arc for receiving a potential to control the same, and means in the path of the auxiliary arc for supplying a potential to said operating arc controlling means.

5. In a control system for electric current rectifiers of the arc type, an electric current rectifier having anodes and a cathode, grids for controlling the arc flowing between the anodes and the cathode, 120 means for producing an auxiliary arc within said rectifier, grids in the path of the auxiliary arc to receive a potential, and means connecting said control grids and said last mentioned grids.

6. In a control system for electric current rectifiers of the arc type, an electric current rectifier having anodes and a cathode, grids for controlling the arc flowing between the anodes and the cathode, an auxiliary 125

current rectifier having anodes and a cathode, grids arranged in said auxiliary rectifier to receive a potential thereon, and means connecting said grids of said main rectifier with said grids of said auxiliary rectifier to control the arc within said main rectifier.

7. In a control system for electric current rectifiers of the arc type, a main electric current rectifier having anodes and a cathode, grids for controlling the arc flowing between the anodes and the cathode, an auxiliary electric current rectifier having anodes and a cathode, grids arranged in said auxiliary rectifier to receive a potential, and means for connecting said grids of said main rectifier and said auxiliary rectifier to supply a positive potential to the grids of the former.

20

8. In a control system for electric current rectifiers, in combination, a main electric current rectifier of the metallic vapor arc type having a cathode and a plurality of anodes constituting electrodes for the flow of arcs therebetween, grids arranged adjacent said anodes for controlling said arcs, an auxiliary electric current rectifier comprising a cathode and a plurality of anodes supported within an electrically conductive casing in insulated relation therewith, the last said cathode and anodes constituting electrodes for the flow of arcs therebetween operable to impress on said casing potentials positive with respect to the potential of the first said cathode, and means for connecting said casing with the first said grids to impress said potentials thereon.
